UNITED STATES PATENT OFFICE.

WILLIAM CRAMER, OF ST. LOUIS, MISSOURI.

FOLDING BED.

Application filed October 12, 1922. Serial No. 594,034.

To all whom it may concern:

Be it known that I, WILLIAM CRAMER, a citizen of the United States of America, a resident of the city of St. Louis, in the State of Missouri, have invented certain new and useful Improvements in Folding Beds, of which the following is a full, clear, and exact description, reference being had to the accompanying drawings, forming a part of

10 this specification.

This invention relates to improvements in folding beds, and more particularly to a bed having foldable end members. One of the objects is to produce a bed of this kind having means whereby the folding motion is transmitted from one end member to another, for example, from an endboard to a leg, so that the bed can be very easily folded. In the preferred form of the invention, the 20 legs and both endboards are united through the medium of operating mechanism, so that the folding motion can be transmitted from any one of these parts to all of the others.

A further object is to produce a simple and 25 effective means for locking the foldable end members.

With the foregoing and other objects in view, the invention comprises the novel construction, combination and arrangement of 30 parts hereinafter more specifically described and illustrated in the accompanying drawings, wherein is shown the preferred embodiment of the invention. However, it is to be understood that the invention comprehends changes, variations and modifications 35 which come within the scope of the claims hereunto appended.

Fig. I is a side elevation showing a portion of a hollow wall and a bed located in a 40 passageway in the wall, the concealed position of the bed being indicated by dot and dash lines.

Fig. II is a vertical section taken approximately on the line II-II in Fig. I.

Fig. III is a horizontal section showing the carriage from which the bed is suspended.

Fig. IV is a fragmentary side elevation showing the locking device mounted in the 50 carriage to lock the counterbalancing device.

Fig. V is a vertical section showing the legs at one end of the bed and portions of the headboard, or footboard, extending upwardly from the legs.

Fig. VI is a side elevation, partly in section, showing approximately one-half of the

bed, and also showing a portion of the hollow wall in which the bed may be concealed.

Fig. VII is a section taken approximately on the line VII-VII in Fig. VI.

Fig. VIII is an enlarged section taken approximately on the line VIII-VIII in Fig. VI, showing the headboard, or footboard, in the position it occupies when folded toward the body of the bed.

Fig. IX is an enlarged side elevation showing a portion of one of the side rails of the bed, and a portion of the means whereby motion may be transmitted from the head to the foot of the bed.

Before describing the bed structure, I will point out the bed compartment and the movable support whereby the folding bed is carried into and out of the compartment.

The hollow wall comprises wall members 1 separated from each other to provide a narrow bed compartment between them. A transverse passageway A is formed through the wall, so as to provide communication between the rooms at opposite sides of the wall. At one of the vertical sides of this passageway, jamb members 2 are separated from each other to form an elongated vertical entrance to the narrow bed compartment in the hollow wall.

3 designates straight horizontal tracks located within the hollow wall and extending from the bed compartment to points above the transverse passageway A in the hollow wall. The bed-supporting carriage comprises a horizontal frame including end members 4 connected together by means of bars 5, which are shown most clearly in Fig. III. This carriage is provided with rollers 6 mounted on the tracks 3 to guide the carriage in a straight horizontal line. A shaft 7 is rotatably mounted in the end members 4 of the carriage, and cams 8 are secured to the ends of this shaft.

9 designates suspension chains depending from the cams 8 and having their lower ends secured to suspension rods 10. The chains 9 are secured to the cams 8 and adapted to engage the peripheral faces thereof. As shown in Fig. II, each chain 9 may pass between guide members 11 and 12 on the carriage, the member 12 being in the form of a roller.

13 and 13' designate pivots extending from a bed (Figs. I and VI), and secured to the suspension rods 10, as will be hereafter described, to form a 105 pivotal support for the bed.

The counterbalancing device comprises a

spring 14 surrounding the shaft 7 (Figs. I and III) and having one of its ends secured to a collar 15, the latter being rigidly secured to the shaft. The other end of the 5 spring is secured to a worm gear 16, loosely mounted on shaft 7 and meshing with a worm 17, said worm being rotatably mounted in bearings extending from one of the end members 4, as shown in Figs. I and III. 10 A vertical stem 18 (Fig. I), depending from the worm 17, may be engaged by a suitable tool to rotate the worm 17, thereby rotating the worm wheel 16 which is secured to one end of the counterbalance spring 14. The 15 wheel 16 is loosely mounted on shaft 7, and it can be thus rotated to vary the tension of spring 14. This means for adjusting the spring is self-locking, for the worm screw 17 can impart motion to the wheel 16, but 20 said wheel cannot impart motion to the screw.

Under certain conditions to be hereafter pointed out, it is desirable to prevent rotation of the shaft 7 to which one end of the 25 spring is secured. The means for locking this shaft comprises a disk 19, rigidly secured to a shaft (Figs. I, II and III), and a bolt 20 adapted to be projected through the disk, the latter having an opening at 21 (Fig. II) to receive the bolt. This bolt is 30 guided by one of the end members 4 and also by a bracket 22 extending from a side member 5 of the carriage, as shown in Fig. III. 23 designates a spring interposed between the bracket 22 and a collar 24 on the rod 20. This spring tends to project the bolt through the disk 19 so as to lock the shaft 7 and the counterbalancing spring 14. The means for unlocking the bolt comprises 35 a bell crank lever 25 (Figs. I and IV) pivotally connected to one of the frame members 5 of the carriage, said lever having a short arm connected to the bolt and a long arm connected to a depending operating cord 40 which can be pulled to withdraw the bolt from the disk 19, thereby unlocking the shaft and counterbalance spring. It will 45 now be understood that when the opening in the disk 19 registers with the bolt 20, the spring 23 will project the bolt through the opening, so as to lock the disk as shown in Fig. IV. The worm 16 can then be turned to 50 adjust the counterbalance spring, or if desired, the bed can be disconnected from the carriage, as will be hereafter pointed out.

The bedstead comprises side rails 27, brackets 28 secured to the ends of the side rails, legs 29 in the form of tubes extending downwardly from the ends of the side rails, and end boards extending upwardly from the legs, one of said boards being a footboard 30 and the other being a headboard 31. Each leg 29 is rigidly secured to a segmental gear 32 pivoted at 33 to one of the side rails 27, and each of the end boards

30—31 is rigidly secured to a segmental gear 34 pivoted at 35 and meshing with one of the gears 32, as shown most clearly in Fig. VI. The footboard, headboard and legs are thus pivotally connected to the bed frame, 70 and they can be moved on their pivots from upright positions to approximately horizontal positions, as suggested in Fig. VI. Motion is transmitted from the foot to the head of the bed through the medium of a small 75 lever 35' (Figs. II, VI and IX) pivoted at 36 to one of the side rails 27 and having its ends pivoted to connecting bars 37. 38 designates pivots connecting the respective bars 37 to gears 32 at opposite ends of the 80 bed, as shown by Figs. II and VI. By means of the connecting device just described and the gears 32 and 34, motion can be transmitted from any one of the legs to the other legs, and also to the footboard 30 85 and headboard 31; or, motion can be transmitted from either of these boards to the other board and also to all of the legs. In other words, when any one of these members is folded or unfolded, a corresponding motion is imparted to all of the other members, so as to simultaneously fold or unfold the legs 29 and boards 30 and 31.

When the legs and the boards 30 and 31 are folded, the boards are pressed upon the 90 bed clothes (not shown) to secure the same, and they are locked in their folded positions through the medium of a ratchet device shown in Figs. V, VI, VII and VIII. The brackets 28 adjacent to the footboard 30 are 95 provided with internal ratchet teeth 39 and adapted to be engaged by dogs 40 secured to springs 41 arranged within the footboard 30 and having their lower ends secured thereto. The free upper end of each spring 100 41 (Figs. V and VI) extends through a bar 42, and these bars are connected together through the medium of an operating lever 43 (Fig. V) pivoted to the footboard 30 and having its ends pivoted to the respective 105 member 42. This lever 43 can be moved about the axis of its pivot to move the bars 42 away from each other, thereby moving the springs 41 to release the dogs 40 from the ratchet teeth 39. When the footboard, 110 headboard and legs are folded, the footboard 30 occupies the approximately horizontal position shown in Fig. VI, so as to engage the bed clothes, and it is then locked through the medium of the dogs 40 cooperating with 115 ratchet teeth 39. Since the footboard is connected to the legs and headboard, it will be understood that the dogs 40 and ratchet teeth 39 serve as means for locking all of these parts. Before unfolding the parts, 120 the lever 43 (Fig. V) is operated to release the dogs 40.

The brackets 28 at the ends of side rails 27 serve as housings for the segmental gears 34, as shown by Figs. V and VI, and each 125

of these housings is open at the top and provided with a closure 44 adapted to move from the position shown by full lines in Fig. VI to the position shown by dot and dash lines. In this view it will be noted that the closure 44 is pivoted at 45 to the footboard 30, and that its lower edge is movable over the lower portion of bracket 28 in response to the folding and unfolding motions of the footboard.

We will now describe the means whereby the footboard, headboard and legs are locked when the bed is unfolded and supported on the floor. The footboard 30 comprises a pair of tubular side members (Figs. V and VI) alined with the legs 29 immediately beneath the same. 46 designates locking arms, each having a locking head 46' arranged partly within the upper end of a leg 29 and partly within the lower end of footboard 30. Each locking arm 46 is pivoted to a bracket secured to one of the side rails 27, as shown in Fig. VI. Each leg 29 at the foot of the bed contains a vertical, slidable locking rod 47 having its upper end engaged with a locking arm 46 and provided with a caster at its lower end. When the parts are positioned as shown in Figs. V and VI, the foot of the bed is supported on the casters at the lower ends of rods 47, and the load is transmitted through these rods to the casters. It will therefore be understood that the rods 47 cooperate with locking arms 46 to retain the heads 46' in the lower ends of the footboard, 30, and the heads 46' then cooperate with the footboard to retain the legs, footboard and headboard in their upright positions. In Fig. VI, note that the footboard 30 is pivoted at 35, and that the head 46' prevents the footboard from moving about the axis of the pivot.

When the bed is lifted from the floor, the locking arms 46 drop by gravity to release the locking heads 46' from the footboard, thereby unlocking the footboard, as well as the headboard and legs, these parts of the bed being operatively connected together, as previously pointed out.

The bed is pivotally connected to the horizontally movable carriage through the medium of pivots 13 and 13' extending through the lower ends of suspension rods 10, and the pivots are located approximately midway between the ends of the bed so as to approximately equalize the weight at opposite sides of the pivots. The counterbalance spring 14 tends to rotate the shaft 7 and its cams 8 on which the suspension chains 9 are mounted, and the power transmitted from the spring tends to lift the bed. Consequently, the bed can be very readily lifted from the floor, and when the pivots 13-13' are high enough, the bed can be easily moved in an arc of a circle about the axis of the pivots to a vertical

position in alinement with the bed compartment in the hollow wall, as shown by dot and dash lines in Fig. II. The bed is then alined with the narrow entrance to the bed compartment, and since it is supported by the horizontally movable carriage, it can be easily moved in a horizontal line parallel with the axis of its pivots 13, so as to pass into the bed compartment.

When the bed is located in the horizontal position shown by full lines in Fig. II, it lies partly within the transverse passageway in the wall and partly within the two rooms at opposite sides of the passageway. However, the bed can be readily disconnected from its suspension members and moved on its casters to any desired position in either of the rooms.

To disconnect the bed, it is necessary to lock the counterbalancing device, and this requires an excess downward movement of one of the suspension members. In Figs. VI and VII, 48 designates a lever pivoted at 49 to a wing 50 secured to one of the side rails 27, and the pivot 13 extends from this lever. After the bed is supported on the floor, the lever 48 is moved downwardly to impart a downward movement to the suspension rod 10 above the pivot 13, thereby imparting motion to the shaft 7 and its locking disk 19 so as to aline the opening in said disk with the spring-pressed locking bolt 20. The bolt then enters the opening in the disk so as to lock the shaft and the counterbalance spring. The suspension rods 10 then hang loosely from the overhead carriage and they can be readily removed from the pivots 13 and 13', so as to disconnect the bed from the carriage. In restoring the bed, the suspension members 10 are applied to the pivots and the lever 48 is again moved downwardly to eliminate friction between the locking bolt 20 and disk 19. The cord 26 is then pulled to withdraw the locking bolt 20 from the disk, thereby permitting the counterbalancing device to act upon the bed.

The counterbalancing spring 14 is wound and unwound in response to vertical movements of the bed, and during the unwinding operation the force of the spring gradually becomes weaker. To compensate for these variations in the spring, the peripheral faces of cams 8 (Figs. II and III) are so formed that the lines of contact between the suspension chains and the cams gradually approach the axis of shaft 7 when the bed is moved upwardly. By winding the chains onto cams in this manner, the effect of the counterbalancing device is to approximately balance the weight of the bed when the latter is located at different elevations relative to the floor.

Closure plates 60 and 61 are secured to the respective ends of the carriage by means of

depending brackets 62, as shown in Figs. I and II. When the bed occupies its concealed position, the vertical plate 60 closes the entrance to the bed compartment, and when 5 the bed is exposed this entrance is closed by the plate 61.

The lever 48 is normally locked to the bed as shown by Figs. VI and VII, a small locking lever 63 being pivoted to said lever 48 10 and provided with a locking pin 64 adapted to be projected through the wing 50. 65 designates a spring (Fig. VII) acting upon lever 63 to yieldingly retain the locking pin 64 in the wing 50. Before detaching the 15 bed, the small lever 63 is actuated to unlock the lever 48, and the latter is then moved downwardly relative to the bed, so as to lock the counterbalancing device, as previously pointed out.

20 I claim:

1. In a folding bed, a bedstead provided with a foldable leg depending from and entirely supported by the bed, a locking member adapted to hold said leg in its unfolded 25 position, and a bed-supporting device cooperating with said locking member to retain the latter in its operative position.

2. In a folding bed, a bedstead provided with a foldable leg depending from and entirely supported by the bed, a locking member adapted to hold said leg in its unfolded position, and a bed-supporting device co-operating with said locking member to retain the latter in its operative position, said 35 bed-supporting device comprising a caster below said leg, and a thrust member extending from said caster to said locking member.

3. In a folding bed, a bedstead provided 40 with a pivotally mounted hollow foldable leg depending from and entirely supported by the bed, a pivotally supported locking member located adjacent to the upper end of said leg to lock the same in its unfolded position, said locking member being adapted 45 to drop by gravity from its operative position, and a bed-supporting device cooperating with said locking member to retain the

latter in its operative position, said bed-supporting device comprising a caster below 50 said leg and a thrust rod mounted in said leg and extending from said locking member to said caster to form a support for the bed.

4. In a folding bed, a bedstead comprising side members, brackets at the ends of 55 said side members, endboards pivotally mounted in said brackets, said brackets having openings at the top to permit pivotal movement of said endboards, and movable closures for said openings, said closures being movable with the respective endboards.

5. In a folding bed, a bedstead comprising side members, brackets at the ends of said side members, endboards pivotally mounted in said brackets, said brackets having openings at the top to permit pivotal movement of said endboards, and movable closures for said openings, said closures being pivotally connected to the respective endboards so as to move along the brackets in response to 70 movements of said endboards.

6. In a folding bed, a bedstead comprising a frame extending from end to end of the bed, pairs of foldable legs pivoted to said frame, a foldable footboard pivoted to 75 said frame, a foldable headboard pivoted to said frame, operating connections whereby the folding motion is transmitted from one of said foldable parts to all of the others, automatic locking means cooperable with one of said foldable parts to automatically and simultaneously lock all of said foldable parts in their folded positions, an additional automatic locking means whereby all of said foldable parts are automatically and simultaneously locked in their unfolded positions, the last mentioned automatic locking means being actuated by the weight of the bed itself, so as to automatically lock the foldable parts when the bed is in service, and a manually controlled member whereby the first mentioned automatic locking means is released.

In testimony that I claim the foregoing I hereunto affix my signature.

WILLIAM CRAMER.
